ATTORNEY

UNITED STATES PATENT OFFICE.

CHARLES H. NEWHALL, OF PROVIDENCE, RHODE ISLAND, ASSIGNOR OF ONE-HALF TO JAMES A. McCOART, OF SAME PLACE.

ELEVATOR.

SPECIFICATION forming part of Letters Patent No. 608,789, dated August 9, 1898.

Application filed December 9, 1896. Serial No. 614,997. (No model.)

To all whom it may concern:

Be it known that I, CHARLES H. NEWHALL, of Providence, in the county of Providence and State of Rhode Island, have invented certain new and useful Improvements in Elevators; and I do hereby declare that the following is a full, clear, and exact description thereof, reference being had to the accompanying drawings, and to the letters of reference marked thereon, which form a part of this specification.

This invention relates to that class of elevator safety attachments in which an electric current is used as the medium through which the parts are operated to produce the desired results.

It is fully explained and illustrated in this specification and the accompanying drawings.

Figure 1 is a perspective view of the elevator-car, the prime motor for raising and lowering the car minus the wire ropes, and the auxiliary motor for controlling the operation of the prime motor and the connecting parts between the two motors. Fig. 2 is a sectional view, on an enlarged scale, of the auxiliary motor, taken vertically through the center of the cylinder and supply-pipe. Fig. 3 is an enlarged view of the devices by which the door of the elevator-well opens and closes the electrical circuit. Fig. 4 is a detail.

The objects of the invention are to provide means whereby, first, that the car shall be incapable of being started if the door of the elevator-well is not closed; second, that if the well-door shall be opened the car will stop wherever it may be at that time; third, if the electric circuit is broken in any place accidentally the car will stop at once if in motion and cannot be started if at rest.

The construction is as follows:

H is the elevator-car.

B is the prime motor, which may be operated by steam or hydraulic pressure, and its connections with the car may be made with wire ropes in any of the usual ways.

D is an auxiliary motor to control the operation of the prime motor and is in this case supposed to be operated by hydraulic pressure.

a is the supply-pipe to the prime motor and

connects the same with a steam-boiler. (Not shown.)

c is the supply-pipe for the auxiliary motor and is connected with a water-main having a suitable pressure.

e e' are passage-ways connecting the supply-chamber s'' with the ends of the cylinder of motor D.

s is the valve-stem, on which are the two upper and lower passage-valves i i' of the motor D, which form a balanced valve in effect.

A bracket n extends out from the motor D to support an electromagnet c', and the valve-stem s extends down between the coils of the electromagnet and has an armature v attached to it under the electromagnet, and an open spiral spring n' is placed on the valve-stem s, between valve-case and a collar on the valve-stem, to push the valve-stem down when not drawn up by the attraction of the magnet on the armature.

d d' are wires forming a circuit with a battery or other source of electricity included in it and are connected with the electromagnet c' to charge it. The prime motor B is started and stopped by a lever F, hung on a rocker-shaft t, held in standards on the top of the motor, and a cord h h' connects it from each side of the shaft with the starting-lever g of the car H. One end of the lever F is extended out and has a chain m, which passes between two pulleys o' o' and is connected to the end of the vertical leg of a knee-lever J, held on a pivot in the lower part of the motor D, the horizontal arm of the knee-lever being connected to the piston-rod of the motor D, so that when that piston is moved up the knee-lever J will be moved to draw on the chain m and pull the lever F up against the two pulleys o' o', so that it cannot be moved in the car by the lever g to start the car, for the drawing of the lever F, whether it be from above or below, to the pulleys closes the valve in the prime motor B, and at the same time a cord a', that has one end made fast to the end of the lower leg of the lever J and is carried out over the pulley a'' and up over to the shut-off valve w in the supply-pipe a of the motor B, will be slackened up, so as to let the valve w be shut by the weight on its lever, so that if the devices directly con-

nected with the lever F fail to operate the shutting of the valve will stop the motor B by shutting off the supply of steam.

In Fig. 3 is shown an enlarged representation of the devices for opening and closing the circuit by the elevator-well door *k*. A socket *n* is attached to the frame of the door *k*, and a bolt *c*'' is fitted to slide therein. The inner half of this bolt is made smaller and has a spring put on to push the bolt out of the socket. The small part of the bolt is made to slide in a hole in the inner end of the socket, so that when the door *k* is closed it will push the bolt out at the inner end and press the disk *v*''', which has one of the circuit-wires *d* attached to it, against the plate *i*'', which has the other circuit-wire *d*' attached to it, and in this way close the circuit, and the operation of the parts will be this: When the door *k* is open, the circuit will be broken by the separation of the disk *v*''', and the electromagnet will not be charged and the spring *n* will be free to push down the valves *i* *i*' and allow the water to enter the lower end of the cylinder of motor D from the supply *s*''' by the passage *e* and force up the piston and move the lower leg of the lever *J* so as to draw the lever F, by the chain *m*, against the pulleys *o* *o*', as described above, and hold it there, so it cannot be moved to start the motor and car. This same condition of things obtains if the circuit is broken accidentally. The car will stop wherever it may be; but when the door *k* of the elevator-well is safely closed the circuit will be closed by the pushing in of the bolt *c*'', as described, and the electromagnet will be charged and draw up the armature *v* and valve-stem *s*, with the valves *i* *i*', and open the upper passage *e*' for the water to enter the upper end of the cylinder and force the piston down and moving the knee-lever *J* to slacken the chain *m* and leave the lever F free to be moved, so that car can be started by the lever *g*. A circuit-breaker *g*' is placed in the car and included in the circuit *d* *d*'. It is constructed like the one for the door *k*, (shown in Fig. 3,) excepting that the wire *d*' instead of being attached to the plate *i*'' is attached to the plate *i*''', as shown in Fig. 4, so that when the starting-lever *g* is moved to a vertical position it will push in the bolt *c*'' and break the circuit, which will cause the car to stop, as above described. It will readily be seen that if the ropes *h* *h*' should be broken, so there would be no control through them of the lever F, the car could still be stopped by putting the starting-lever *g* into a vertical position through the breaking of the circuit at *g*', as just described.

This mechanism for stopping the car or preventing it from starting is not intended to interfere in any way or to have any connection with the operation of the devices

usually attached to elevator-cars to prevent the car from falling when the rope that hoists the car breaks.

Having thus described my improvements, I claim as my invention and desire to secure by Letters Patent—

1. In an elevator safety attachment, the combination of: a lever, as F, to operate the valve of the prime motor, an operating device on the car, a connection between said lever and said operating device, an auxiliary motor, a knee-lever as J having one leg connected with the piston of said auxiliary motor and the other leg of the lever connected with said lever F, a balanced valve to admit the water to either end of the cylinder of the auxiliary motor, an electromagnet to draw the valve in one direction and a spring to move it back, a circuit for an electric current to charge said electromagnet by closing the door of the elevator-well, substantially as described.

2. In an elevator safety attachment, the combination of: a lever, as F, to operate the valve of the prime motor, an operating device on the car, a connection between said lever and said operating device an auxiliary motor, a knee-lever as J having one leg connected with the piston of said auxiliary motor and the other leg of the lever connected with the said lever F, a balanced valve to admit the water to either end of the cylinder of the auxiliary motor, an electromagnet to draw the valve in one direction and a spring to move it back, a circuit for an electric current to charge said electromagnet by closing the door of the elevator-well, a circuit-breaker connected with said circuit and attached to the car in position to be operated by the operating device substantially as described.

3. In an elevator safety attachment, the combination of: a lever, as F, to operate the valve of the prime motor, an operating device on the car, a connection between said lever and said operating device an auxiliary motor, a knee-lever as J having one leg connected with the piston of said auxiliary motor, and the other leg of the lever connected with the lever F, a balanced valve for said auxiliary motor an electromagnet to draw the valve in one direction and a spring to move it back, a circuit for an electric current to charge said electromagnet to be operated by closing the door of the elevator-well, a cord as *a*' attached at one end to said knee-lever and the other end attached to the shut-off valve in the supply-pipe of the prime motor, substantially as described.

In testimony whereof I have hereunto set my hand this 5th day of December, A. D. 1896.

CHARLES H. NEWHALL.

In presence of—

HOWARD E. BARLOW,
BENJ. ARNOLD.
